UNITED STATES PATENT OFFICE.

JAMES H. BUSELL, OF BOSTON, MASSACHUSETTS, ASSIGNOR TO HOMER ROGERS, TRUSTEE, OF SAME PLACE.

HEEL-TRIMMER.

SPECIFICATION forming part of Letters Patent No. 390,750, dated October 9, 1888.

Application filed December 18, 1886. Serial No. 222,005. (No model.)

To all whom it may concern:

Be it known that I, JAMES H. BUSELL, of Boston, in the county of Suffolk and State of Massachusetts, have invented a new and useful Heel-Trimmer, of which the following is a specification, reference being had to the accompanying drawings, in which—

Figure 1 is an axial section of my trimmer in the preferred form. Fig. 2 is a front view 10 of the same. Figs. 3 and 4 are details. Figs. 5 and 6 are views, like Figs. 1 and 2, of a modified form of my trimmer. Figs. 7 to 14, inclusive, are diagrams for illustration.

The main feature of my invention consists 15 in the combination of a rotary cutter with a rand-knife and recessed guard, the blades of the rand-knife moving between blades of the cutter, and the rand-knife and recessed guard yielding with relation to the cutter as the heel 20 varies in height, as more fully set forth hereinbelow.

Minor features of my invention are set forth 25 hereinafter.

In the drawings, A is the main cutter for 30 trimming the edge of the heel.

D is the rand-knife, E the guide for the corner of the top lift, and F the recessed rand guide or guard; for this part F performs a double function—that is, it is a guide to enter 35 and guide by the rand (or the angle between the heel and upper-leather) and also a guard to prevent the heel-seat end of cutter A (and the rand-knife D, when used) from injuring the upper-leather of the boot or shoe.

Both the rand-guide F and the rand-knife D 40 are so mounted that they will move sidewise as the heel varies in height—that is, the length of cut varies, being shortest near the corners formed by the breast and edge and longest at the rear of the heel; and I am the first, so far I know, to use a rand-knife and heel-edge cutter self-adjusting to these variations in the height of the heel, and also the first to produce a rotary cutter for finishing heel-edges by 45 using the corner of the top lift as a guide, in which the rand-guide is cupped to receive the heel-seat end of the cutter, and the parts are relatively self-adjusting to suit variations in the height of the heel.

It will be obvious that the cutter A and the

guide E for the corner of the top lift must always remain in close contact, in order that the corner of the top lift may be used as a pattern-plate; but it will be equally clear that my invention may be embodied in a device in which 55 the cupped rand-guide F (and its rand-knife D, when used) has no sidewise motion, but the cutter A and top-lift guide E move sidewise away from the cupped rand-guide F; moreover, that both the cupped rand-guide F and 60 the cutter A with its top-lift guide E may have lateral motion; but the best form of my invention is that shown in the drawings, in which the cutter A and its guide E for the corner of the top lift have no lateral motion, 65 and all the lateral motion is given to the cupped rand-guide F and its rand-knife D.

In the machine shown in Figs. 1 and 2 of the drawings, cutter A revolves with shaft B and has no lateral motion on that shaft. The 70 guide E for the corner of the top lift may revolve with shaft B, or be held stationary, as will be well understood by all skilled in the art, but must, of course, always stand close up to the side of cutter A, so that the short wall 75 of the guide E will be substantially flush with the cutting-edges of cutter A. (See Bussell patent, No. 308,056, November 18, 1884.) The hub f^2 of the recessed rand guide F is shown as mounted on a sleeve, B², which loosely fits the 80 outer end of shaft B, so that the rand-guide F and the sleeve B² may move laterally until they strike the head of screw B³. This sleeve B² is splined to the shaft B, and therefore revolves with it when the rand-knife D is used, 85 for the rand-knife D is made fast to sleeve B² by screws f^2 , as it must, of course, revolve in order to cut out the rand. The recessed rand-guide F, I have shown as a cup; but it may of course be a segment. It is preferable in practice to make it a complete cup when the rand-knife D is used with it; but when not so used, as is the case in some kinds of heels, it may be a small segment, as will be clear to all skilled in the art. The heel-rest G is supported in 90 any suitable way, too well known to require further description.

In Figs. 5 and 6 the cutter A is mounted on shaft B, which is hollowed out to receive a spindle, B', carrying rand-knife D. Spindle 100

B' is kept in the opening in shaft B and compelled to rotate with shaft B by means of a pin, b', passing through slot b in spindle B'. The guide E is mounted on shaft B at one end of 5 the cutter, and the guide E, cutter A, and rand-knife D all rotate together, the blades d of the rand-knife moving back and forth between the blades a in cutter A, according to the variations in the height of the heels. The 10 rand-knife D is clamped against a shoulder on spindle B' by means of a sleeve, B², and a screw, B³, which passes through the sleeve into the end of the spindle. On sleeve B², between the head of screw B³ and a shoulder on sleeve B², 15 is loosely mounted my recessed rand-guide F, whose hub f² is slightly shorter than sleeve B², so that the rand-guide does not rotate with the rand-knife when the heel-trimmer is in use, as will be clear to all skilled in the art; but the 20 rand-knife and rand guide yield together to suit variations in the height of the heel, the recessed rand-guide receiving more or less of the heel-seat end of the cutter as the heel varies in height.

25 The operation of my trimmer is as follows: The operator places the corner of the top lift in the angle of the guide E and tips the shoe so that the rand-guide, if both are used, enter between the heel and upper. The heel 30 is held against the trimmer and upon the rest G and turned by hand to present the edge properly, and, as the heel varies in height and the rand-guide and rand-knife together yield with relation to the cutter and guide E, the 35 heel is properly trimmed. The rest G aids the workman in supporting the heel under the blows of the blades of the cutter, which revolves with great speed, commonly about six thousand revolutions per minute. The yielding 40 of the rand-knife to and from the heel-rest G is one of the main objects of my invention, and my trimmer is the first, so far as I know, in which this important feature is found.

The diagram, Figs. 7 to 14, illustrate most 45 of the various manners of using my trimmer—that is, in Fig. 7 the trimmer is adapted to take out the rand; but the top lift is not used as a pattern. Fig. 8 is the same as Fig. 7, except that the heel-rest is used. Figs. 11 and 50 12 are like Figs. 7 and 8, except that no rand-knife is used. Figs. 9 and 10 are like Figs. 7

and 8, except that the top lift is used as a pattern. Figs. 13 and 14 are like Figs. 9 and 10, except that no rand-knife is used.

In some factories only one of the forms of 55 my trimmer shown in Figs. 7 to 14 is needed, while in others two or more of them are requisite, depending, as will be clear, upon the style and quality of heels made.

I am aware of the following patents: No. 60 234,869, to Helms, November 30, 1880; No. 330,008, to Gallagher, November 10, 1885; No. 209,787, to Adams, November 12, 1878; No. 322,945, to Manley, July 28, 1885; No. 282,857, to Dean, August 17, 1883, and disclaim all that 65 is shown in them.

What I claim is—

1. In combination, rotary cutter A, having blades a, rand-knife D, having blades d projecting between the blades a of cutter A, near 70 the heel-seat end of the cutter, and recessed guard F, covering a portion of the heel-seat end of the main cutter A, guard F, and rand-knife D, yielding together with relation to cutter A as the height of the heel varies to 75 cause the uncovered edges of the blades a and the position of blades d with relation to the heel-seat portion of the cutter A to vary as the height of the heel varies, all arranged and operating substantially as and for the purpose 8c specified.

2. In combination, cutter A, top-lift guide E at the top-lift end of cutter A, rand-knife D, with its blades d projecting between blades a, near the heel-seat end of cutter A, and 85 recessed guard F, the guard F and rand-knife D yielding together with relation to cutter A and top-lift guide E, all arranged and operating substantially as and for the purpose specified.

3. In combination, cutter A, top lift guide 90 E at top-lift end of cutter A, rand-knife D, with its blades d projecting between blades a, near the heel-seat end of cutter A, recessed guard F, and heel-rest G, the guard F and rand-knife D yielding together with relation 95 to cutter A and top-lift guide E, all arranged and operating substantially as and for the purpose specified.

J. H. BUSELL.
